[57] CLAIM

The ornamental design for a dunnage bag and valve therefor, as shown and described.

DESCRIPTION

FIG. 1 is a perspective view of a dunnage bag and valve therefor showing my new design;

FIG. 2 is a top side plan view thereof;

FIG. 3 is a bottom side plan view thereof;

FIG. 4 is a right side elevational view thereof;

FIG. 5 is a left side elevational view thereof;

FIG. 6 is a front side elevational view thereof;

FIG. 7 is a back side elevational view thereof;

FIG. 8 is a perspective view thereof showing my new design in an alternate embodiment;

FIG. 9 is a top side plan view thereof;

FIG. 10 is a bottom side plan view thereof;

FIG. 11 is a right side elevational view thereof;

FIG. 12 is a left side elevational view thereof;

FIG. 13 is a front side elevational view thereof; and,

FIG. 14 is a back side elevational view thereof.

The length and width of the bag are shown broken away in the views to indicate indeterminate size.
